UNITED STATES PATENT OFFICE.

JOSEPH L. HOFFMAN, OF PORTLAND, OREGON.

FURNACE.

1,115,672.

Specification of Letters Patent. Patented Nov. 3, 1914.

Application filed January 22, 1914. Serial No. 813,611.

To all whom it may concern:

Be it known that I, JOSEPH L. HOFFMAN, a citizen of the United States, residing in the city of Portland, county of Multnomah, 5 and State of Oregon, have invented certain new and useful Improvements in Furnaces, of which the following is a specification.

This invention relates to furnaces, and more particularly to certain improvements 10 therein to better adapt them for burning paper, boxes, and rubbish in a way which will completely consume the smoke and light particles of combustion and thereby prevent the escape to and through the chimney of unnecessary smoke, flying ash, soot, 15 and the like.

In department stores and other like establishments there is always a considerable amount of paper, paste-board and wooden 20 boxes which must be burned in the furnace. This rubbish will, of course, generate considerable heat, but under present arrangements there is cause for much objection by reason of the fact that paper ash and soot 25 therefrom escape into the atmosphere. I have conceived the idea of so constructing and arranging a furnace that such paper and rubbish can be conveniently put thereinto and burned upon the grates thereof, 30 with an oil blaze discharging above and over the same, preferably from the rear, so that all of the smoke, ash and light carbon particles from such rubbish fire must necessarily pass through an intense oil fire and 35 thereby be completely consumed, such oil fire operating as a most effective smoke consumer. Thus all the heat units from this rubbish can be effectively and advantageously utilized, with a certain saving in 40 other fuel.

In order that others may fully understand my improvements in furnaces, I have shown one practical embodiment thereof in the accompanying drawings, which I will now describe.

Figure 1 is a vertical sectional view, taken on line 1-1 of Fig. 2, through a furnace embodying my invention; Fig. 2 is a horizontal sectional view on line 2-2 of Fig. 1; 50 Fig. 3, is a cross sectional view taken on line 3-3 of Fig. 1.

The general construction and arrangement of the furnace and boiler may be of any desired type. As shown here for purposes of illustration, the boiler A and boiler 55 pipes B are inclosed in the usual masonry

construction. The heat and products of combustion from the fire-box C follow the course of travel through the pipes B, as indicated by the arrows, and finally escape 60 through D to a chimney or other discharge.

In the fire-box are the usual grates, 1-1, below which is the ash pit 2, with a door 3 opening thereinto. A door 4 opens into the fire-box above the grates. Supply pipes 5 65 and 6, for oil and steam, respectively, are inserted through the front of the furnace, as at 7, and extend rearwardly therein upon the grates 1-1, as indicated, said pipes being protected by a masonry box or cover, as 8. In the construction here shown, the oil supply pipe passes through the steam pipe 6, to the rear of the fire-box. Here they are connected with an oil burner, as 9, extending upwardly and then forwardly, in 75 the manner indicated, whereby the combustible mixture from the burner is discharged across the grates and sufficiently above the same to give room on the grates for burning the rubbish and other hard fuel. Across the 80 rear of said fire-box, in front of said burner, is a back wall, as 10, Fig. 3, with air openings 11, therethrough. Mounted upon the upper edge of said back wall 10, and across the rear of said fire-box is a plate, as 12, 85 through which said burner 9 projects, as indicated. Over the burner, in the middle portion of the rear of said fire-box, and upon said plate 12, is a box like cover 13, 90 from under which said oil burner 9 discharges its combustible mixture, as indicated by the lines leading therefrom. Air from the ash pit below, not only passes up through the grates 1-1, in the usual manner, but also passes upwardly at the back of the ash 95 pit and thence forwardly through the openings 11, in the back wall 10, above the grates 1-1, in front of the oil burner. I have also shown arranged in the fire-box and crosswise thereof, water heating pipes 14, which are positioned so as to be heated from the rubbish fire, or from any grate fire, as in the summer time, when the oil fire is not in use.

In order to protect said water pipes 14 from the intense heat from the oil burner, I cover them with brick, or other masonry, as at 15. By this arrangement, it will be seen that rubbish of all kinds can be burned upon the grates 1-1, in the usual manner, but that the smoke and light carbon particles rising therefrom must necessarily pass through a very intense oil heat above, whereby they

are completely consumed, and do not even get to the boiler pipes and boiler above.

I do not limit the invention to the particular embodiment here shown for purposes 5 of illustration, except as I may be limited by the hereto appended claims.

I claim:

1. In combination with the firebox and grate of a furnace, an oil burner in the rear 10 of said firebox, above said grate, having a forwardly directed nozzle, a plate beneath said nozzle and through which said burner projects with air opening theretaround, a wall member in front of the burner body 15 beneath said plate member, and a cover over the burner nozzle and open forwardly thereof, whereby said burner nozzle discharges above said plate from under said cover and entrains air from the space below the grate 20 around its body portion through said plate, substantially as described.

2. In combination with the firebox and grate of a furnace, a floor-like structure ar-
ranged in said firebox at a space above said 25 grate, an oil burner in the rear of said fire-
box, projecting through an opening in said
floor-like member and provided thereabove
with a forwardly directed nozzle, a cover-
ing over said nozzle and open forwardly
thereof and from under which said nozzle 30
discharges, a wall member in front of said
burner body, beneath said floor-like member,
and having air openings therethrough, and
providing an air passageway upwardly from
the space below the grate around the burner 35
body, substantially as described.

Signed at Portland, Oregon, January
16th, 1913.

JOSEPH L. HOFFMAN.
